Specification of Letters Patent.

Patented Jan. 1, 1918.

Original application filed February 5, 1915, Serial No. 19,209. Divided and this application filed May 28, 1917. Serial No. 171,132.

To all whom it may concern:

Be it known that I, JONAS NORTHRUP, a citizen of the United States, residing at Hopedale, in the county of Worcester and 5 State of Massachusetts, have invented certain new and useful Improvements in Shuttles; and I do hereby declare the following to be a full, clear, and exact description of the invention, such as will enable others 10 skilled in the art to which it appertains to make and use the same.

The present invention relates to an improvement in shuttles for looms, and more particularly to an improvement in the bobbin or filling carrier holding jaws of self-threading shuttles for automatic looms.

The present application is a division of application Serial N. 19,209, filed February 5, 1915.

20 Bobbin holding springs, as commonly constructed heretofore, have been of heavy forged steel and machined into the proper shape to secure the requisite resiliency. This method of constructing the springs is expensive. It has, accordingly, been proposed to reduce the expense in the production of bobbin holding springs by making them of flat stock bent into the required shape. One difficulty hitherto experienced in the use of 25 flat stock for bobbin holding springs has lain in the fact that they have not possessed the necessary resiliency. The object of the present invention, therefore, consists in constructing bobbin holding springs of flat stock in such a manner as to secure the necessary resiliency.

The preferred form of the invention is illustrated in the accompanying drawings, in which Figure 1 is a top plan of the thread 40 delivery and bobbin holding ends of a shuttle with the middle portion thereof removed, showing the application of the structure of the present invention to the bobbin holding end of the shuttle; Fig. 2 is a longitudinal section of the bobbin holding end of the shuttle, partly in elevation; and Fig. 3 is a section on line 3-3 of Fig. 1.

In the illustrated embodiment of the invention the shuttle 5 is, in general, of the 45 usual form of construction, having an elongated bobbin recess 6, and is provided at its thread delivery end with a threading block designated generally by the reference character B. The threading block is held

in place by a screw 7 which passes through 55 a slot formed transversely in the bottom of the block. A piece of felt 8 serves to maintain a tension on the thread as it unwinds from the bobbin, in order that the proper selvages may be formed. The threading block at the thread delivery end of the shuttle may be of any usual or preferred construction. At the bobbin holding end of the shuttle, bobbin holding springs or jaws 10 are provided which constitute the sub- 60 ject-matter of the present invention.

The bobbin holding jaws or springs 10 are made of a strip of flat stock, the ends being bent U-shaped, the bottom of the U being somewhat elongated into a narrow neck 11 70 and receiving between the depressed sides a block 12 for solidity. The neck 11 of the holding jaws is received in a recess in the bobbin holding end of the shuttle and secured therein by the screw 13. The parallel 75 sides of the jaws are provided with notches or recesses 15 into which are received the rings on the bobbin in the usual manner for holding the bobbin in operative position. Heretofore, bobbin holding jaws constructed 80 of flat stock have lacked the resiliency of the forged and machined jaws, the sides of which taper gradually from their base. The present invention secures this proper resiliency by chamfering the top inside edges 85 of both jaws so that the chamfer tapers gradually from about the point 16 at the base of each jaw to about the point 17, from whence outward to their ends the sides of the jaws run parallelly. From the point 90 17 the chamfer or bevel proceeds to the ends of the jaws parallel with their top edges. The result of chamfering the jaws in this manner, as it is obvious, is the removal of 95 the greater amount of stock from the extremity of the jaws where the greater resiliency is desired and the lesser amount of stock from the base of the jaws where a lesser resiliency and a greater strength are desired. Bobbin-holding jaws constructed in this 100 manner have all the advantages of jaws constructed of forged steel machined into proper shape. Another advantage of the bevel or chamfer on the top inside edges 105 of the sides of the bobbin-holding jaws lies in the ready entrance it affords to the bobbin during the filling replenishment.

As indicated in the preamble, the present

invention is not limited to use in connection with shuttles adapted solely for employment in automatic weft replenishing looms, inasmuch as the spring bobbin holding jaws while being especially adapted for use in weft replenishing looms, may be used in connection with other looms.

Having thus described the present invention, what is claimed as new is:—

10. 1. A loom shuttle for the automatic insertion of a filling carrier or bobbin, having U-shaped bobbin holding jaws, recesses in the jaws for maintaining the bobbin in operative position, and deep chamfers on the top inside edges of the parallel sides for the ready insertion of the bobbin.
2. A loom shuttle for the automatic insertion of a filling carrier or bobbin, having U-shaped bobbin holding jaws, recesses in the jaws for maintaining the bobbin in oper-

ative position, and a chamfer on the top inside edges of the jaws beginning at the bottom of the rounded portion of the jaws and tapering downwardly to about the parallel sides of the jaws, from which point to the ends of the jaws the chamfer runs parallel with the top edges of the jaws for imparting the proper resiliency to the jaws.

3. A loom shuttle having, in combination, U-shaped bobbin holding jaws, recesses in the jaws for maintaining the bobbin in operative position, and a chamfer on the top inside edges of the jaws tapering gradually from the bottom of the rounded portion of the jaws to about the beginning of the parallel sides of the jaws, from which point to the ends of the jaws the chamfer runs substantially parallel with the top edges of the jaws.

JONAS NORTHROP.
